R. W. DISBRO

ELEVATOR INCLOSURE

Filed April 25, 1921

FIG. 1.

FIG. 2.

Inventor
Roger W. Disbro
by Fay, Oberlin & Fay
Attorneys.

Patented Apr. 29, 1924.

1,491,985

UNITED STATES PATENT OFFICE.

ROGER W. DISBRO, OF CLEVELAND HEIGHTS, OHIO, ASSIGNOR TO THE W. S. TYLER CO., OF CLEVELAND, OHIO, A CORPORATION OF OHIO.

ELEVATOR INCLOSURE.

Application filed April 25, 1921. Serial No. 464,435.

To all whom it may concern:

Be it known that I, ROGER W. DISBRO, a citizen of the United States, and a resident of Cleveland Heights, county of Cuyahoga, and State of Ohio, have invented a new and useful Improvement in Elevator Inclosures, of which the following is a specification, the principle of the invention being herein explained and the best mode in which 10 I have contemplated applying that principle, so as to distinguish it from other inventions.

This invention relates to elevator inclosures, and more particularly to improvements in the construction of the metallic frame 15 of such inclosures. Ordinarily the metallic frame comprises an angle piece, commonly known to the trade as the "buck," which is attached in place against the ends of the wall at either side of an elevator inclosure, 20 and an ornamental trim strip, which is secured to the buck by screws and nuts or similar means.

This invention has for its general object to provide in a single metallic strip a 25 combination of both the buck and trim strips, which will be comparatively simple and inexpensive to manufacture, will be ornamental in appearance, and which may be secured in place on the end of a wall without the application of supplemental fastening means.

A further object of the invention is to provide a sanitary, dust proof buck and trim strip, having no complicated curves or crevices, which is especially adapted for use in 35 hospitals.

With the above and other objects in view I have devised the novel combination buck 40 and trim strip which I will now describe, referring to the accompanying drawing forming a part of this specification and using reference characters to indicate the several parts. To the accomplishment of the foregoing and related ends, said invention, then, consists of the means hereinafter 45 fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:—

Fig. 1 is a fragmentary perspective view,

partially in section, taken horizontally through by novel buck and trim strip as in use, and

Fig. 2 is a horizontal section, on an enlarged scale, of the parts seen in Fig. 1. 60

In the drawing is illustrated a single embodiment of my invention, which is particularly adapted for use in elevator inclosures in hospitals. The novel strip is so designed that there are no complicated curves or sharp acute angles which would be apt to catch and retain dust. While this embodiment of the invention only, is to be described, it will be obvious that various modifications are possible within the spirit 65 and scope of the claim, hereunto appended. 70

In Fig. 1 is shown a wall 10 at either side of an elevator inclosure, the wall being faced by plaster 11 or other covering substance on either side. The rear side of the 75 wall at its end is usually provided with a niche or cut away portion 12 in which is received the sliding doors, (not shown) of the elevator inclosure.

My novel metallic buck and trim strip 80 13 is substantially U-shaped in cross section, the bridge or connecting portion 14 thereof being designed to fit onto the end 15 of the wall. An offset portion 16 is formed in the buck to conform with the niche 85 12 in the end of the wall. The sides 17 and 18 of the U-shaped strip are adapted to be against the front and back surfaces of the wall, said sides being embedded in the plaster, as at 19, if desired to have the strip 90 flush with the surfaces of the wall. The

side 17 of the buck and trim strip, which is the one at the front of the inclosure, is formed with an outwardly projecting trim bend 20, and has its extreme end 21 bent 95 inwardly toward the wall. In attaching the strip to the end of the wall, the end 21 is forced into and concealed in the plaster. It will be noted that by such construction, the buck and trim strip is held rigidly in place against the end of the wall, without the use of screws or other fastening means, the end 21 anchored in the plaster being adapted to prevent the strip from being removed. 100

It will be apparent from the foregoing that I have accomplished the objects primarily stated and that I have provided a novel one-piece sanitary buck and trim strip, 105 which may be readily secured in place on 110

the end of a wall without utilizing screws or the like.

Other modes of applying the principle of my invention may be employed instead of the one explained, change being made as regards the mechanism herein disclosed, provided the means stated by any of the following claims or the equivalent of such stated means be employed.

10. I therefore particularly point out and distinctly claim as my invention:—

In combination, a wall having a coating of plaster on either side thereof, and a substantially U-shaped unitary metallic buck 15 and trim strip, said strip fitting against the

end portion of said wall and extending about the two sides thereof, one such extending portion of said strip being embedded in such plaster coat on one side of said wall and being flush therewith, and the other extending portion of said strip being provided with an outwardly projecting trim bend, said trim extending longitudinally of said strip and being spaced from said wall, said last named extending portion also having 25 its end bent inwardly to provide an angular flange which extends through said plaster coat.

Signed by me, this 7th day of April, 1921.

ROGER W. DISBRO.
